(57) **CLAIM**

I claim the ornamental design for a sanitization device for footwear, as shown and described.

DESCRIPTION

FIG. 1 is a top right perspective view of a sanitization device for footwear in an open configuration showing my new design.

FIG. 2 is a right side view thereof, the, the left side view being a mirror image.

FIG. 3 is a top front left perspective of the sanitization device for footwear, shown in a closed position.

FIG. 4 is a right side view thereof with the handle in the closed position.

FIG. 5 is a right side view thereof with the handle in the exposed position.

FIG. 6 is a left side view thereof with the handle in the closed position.

FIG. 7 is a left side view thereof with the handle in the exposed position.

FIG. 8 is a front view thereof with the handle in the closed position.

FIG. 9 is a front view thereof with the handle in the exposed position.

FIG. 10 is a rear view thereof with the handle in the closed position.

FIG. 11 is a top view thereof; and,

FIG. 12 is a bottom view thereof.

The broken lines in the figures are for the purpose of illustrating portions of the sanitization device for footwear and form no part of the claimed design.
